REMOTE EXTERNAL HOUSING FOR A READ-OUT DEVICE FOR METERS

Paul Specht, Chicago, Ill., assignor to Worthington Corporation, Harrison, N.J., a corporation of Delaware

Filed Oct. 26, 1966, Ser. No. 4,430

Term of patent 14 years

(Cl. D26—1)

FIG. 1

FIG. 2

FIG. 3

FIGURE 1 is a front elevational view of a remote external housing for a read-out device for meters, showing my new design;

FIGURE 2 is a side elevational view of the remote external housing of FIGURE 1; and

FIGURE 3 is a perspective view of the remote external housing of FIGURE 1.

The rear of the housing is substantially flat and plain in appearance.

I claim:

The ornamental design for a remote external housing for a read-out device for meters, as shown and described.
